UNITED STATES PATENT OFFICE.

ARTHUR SIMON, OF MILWAUKEE, WISCONSIN, ASSIGNOR TO THE CUTLER-HAMMER MFG. CO., OF MILWAUKEE, WISCONSIN, A CORPORATION OF WISCONSIN.

VARIABLE-VOLTAGE TRANSFORMER.

1,227,844.

Specification of Letters Patent. Patented May 29, 1917.

Application filed July 3, 1915. Serial No. 37,988.

To all whom it may concern:

Be it known that I, ARTHUR SIMON, a citizen of the United States, residing at Milwaukee, in the county of Milwaukee and 5 State of Wisconsin, have invented new and useful Improvements in Variable-Voltage Transformers, of which the following is a full, clear, concise, and exact description, reference being had to the accompanying 10 drawing, forming a part of this specification.

This invention relates to improvements in variable voltage transformers.

More particularly the invention relates to 15 projecting arc lamp transformers but it will be apparent that transformers embodying various features of the invention may be advantageously employed in other relations.

One of the objects of the invention is to 20 provide an inclosed transformer of simple, compact and durable construction.

A further object is to provide an adjustable transformer capable of voltage regulation between predetermined limits in very 25 minute degrees.

The accompanying drawing illustrates 30 one embodiment of the invention and the same will now be described, it being understood that the invention is susceptible of various modifications falling within the spirit and scope of the appended claims.

Figure 1 is a top view of the transformer with a portion thereof broken away.

Fig. 2 is a front view thereof.

Fig. 3 is a sectional view taken along the 35 lines 3—3 of Fig. 1.

Fig. 4 is a front view of the transformer with the cover removed, and

Fig. 5 is a diagrammatic view showing the 40 transformer connected in a lamp circuit.

Briefly described, the transformer includes coils 1 and 2 mounted on a core 3 and provided with an adjustable armature 4, all of the aforesaid elements being mounted in 45 an inclosing casing comprising a bottom section 5 and a top section 6.

More specifically considering the above mentioned elements, the core 3 as best shown in Figs. 3 and 4, comprises an E-shaped 50 structure having legs 7, 8 and 9, the legs 7 and 9 having the coils 1 and 2 respectively mounted thereon. The core 3 is preferably built up of laminations 10 confined between side plates 11 fastened together by rivets 12

and secured by screws 13 to lugs 14 projecting upwardly from the bottom of the casing section 5. It is to be here noted that the central leg 8 of the core 3 is shorter and of smaller cross sectional area than the legs 7 and 9, functioning in a manner which will 55 be hereinafter set forth.

The armature 4 comprises a rectangular bar of sufficient length to extend across the legs 7 and 9 of the core 3 and is preferably built up of laminations 16 confined between 60 side plates 17 and fastened together by rivets 18. The armature 4 is slidably mounted between a shoulder 19 within casing section 6 and an elongated lug 20 projecting upwardly from the bottom of casing section 70 5 and is provided with an adjusting screw 21. The screw 21 as best illustrated in Fig. 1, is connected to the armature 4 by a threaded nut 22 formed by projecting the side plates 17 of the armature 4 beyond the 75 laminations 16 and bending the same at right angles toward each other in an overlapping relation. The screw 21 passes through an opening 23 in the end wall of casing section 6 and is secured against endwise movement by a knob 24 on the outside of said section 6 and a shoulder 25 on the inside thereof. Rotation of the knob 24 rotates the screw 21 which through its screw threaded engagement with the nut 22 produces endwise adjustment of the armature 80 4 for a purpose which will be hereinafter set forth. In practice there is considerable tendency for the armature 4 to vibrate and in order to prevent undue vibration the 90 same is provided with a leaf spring 26 having reflexed ends 26^a adapted to bear against the side wall of casing member 6 and resiliently hold the armature 4 in engagement with the core 3.

Before proceeding further the function and operation of the transformer will be described in connection with Fig. 5. As before stated the transformer is particularly adapted for use with projecting arc lamps 100 and in Fig. 5 a lamp is diagrammatically illustrated as provided with carbons 27 and 28 connected by conductors 29 and 30 to the terminals of the coil 2. The coil 1 is connected across the lines L and L' and functions as the primary coil of the transformer to generate lines of force which passing through the coil 2, or secondary coil of the 105

transformer, excites the latter. However, due to the E-shaped construction of the core 3 two magnetic circuits are provided for the lines of force generated by the primary coil 1, one extending through the leg 9 and the other in shunt thereto through the leg 8. It will be understood by those skilled in the art that if the magnetic reluctance of the circuit passing through the leg 9 is varied 5 the ratio between the number of lines of force passing through this leg and those passing in shunt thereto through the leg 8, will vary and produce a variation in the induced voltage of the coil 2. The reluctance of the magnetic circuit passing through the leg 9 is varied by the armature 4 which is adjusted endwise to vary the contact surface between the same and the end of the leg 9. An increase in contact area between 10 these parts will effect a decrease in the magnetic reluctance of the circuit therethrough and a decrease in contact area will increase the reluctance thereof. It is therefore obvious that movement of the armature 4 toward its extreme right hand position as 15 shown in full lines in Fig. 5 increases the number of lines of force passing through the leg 9 thereby effecting an increase in the induced voltage of the coil 2 while movement toward the left hand position as shown in dotted lines produces an opposite effect. It is to be here noted that the voltage limits 20 between which the transformer is adapted for regulation is determined by the relative 25 reluctances of the magnetic circuits passing through the legs 8 and 9. In the transformer illustrated it is desired when the armature 4 is in its extreme right hand position, that the reluctance of the magnetic 30 circuit passing through the leg 8 be high in comparison to that of the circuit passing through the leg 9. The magnetic reluctance of the circuit passing through the leg 8 is made relatively high by making it 35 shorter than the legs 7 and 9, to provide an air gap between the same and armature 4 and also by making the cross sectional area thereof relatively small in comparison to leg 9. Here it should be noted that by 40 slightly adjusting the armature 4 endwise the secondary voltage can be regulated in very minute degrees and that the screw 21, due to its threaded engagement with the armature 4 enables a very fine adjustment 45 thereof.

Again referring to the mechanical structure it will be observed from Figs. 1 and 2 that the casing sections 5 and 6 each comprise a rectangular box-like member having 50 ventilating openings 31 therein. The casing sections 5 and 6 are secured together by screws 32 passing through the front wall of the casing section 6 and engaging tapped lugs 33 on the inside of the casing section 5. The 55 casing section 5 is provided on opposite

ends with openings containing insulating bushings 34 for the reception of conductors and is also provided with a projection 35 for limiting adjustment of the armature 4 toward the left.

It will of course be understood that the specific transformer above described is to be considered merely as illustrative of the present invention and that the same is susceptible of various modifications falling within the scope of the appended claims.

What I claim as new and desire to secure by Letters Patent is:

1. In a variable voltage transformer, in combination, a primary coil, a secondary coil, an E-shaped core therefor, said coils being separately mounted on two legs of said core, the third leg of said core providing a magnetic shunt for said primary coil and an armature bridging all of said legs, said armature being adjustable to increase and decrease the reluctance of the magnetic circuit passing through the leg of said secondary coil to respectively decrease and increase the induced voltage of said secondary coil.

2. In a variable voltage transformer, in combination, a primary coil, a secondary coil, an E-shaped core therefor, said coils being separately mounted on the end legs of said core, the middle leg of said core providing a magnetic shunt for said primary coil and an armature bridging all of said legs, said armature being adjustable to increase and decrease the reluctance of the magnetic circuit passing through the leg of said secondary coil to respectively decrease and increase the induced voltage of said secondary coil.

3. In a variable voltage transformer, in combination, a primary coil, a secondary coil, an E-shaped core therefor, said coils being separately mounted on two legs of said core and the third leg of said core providing a magnetic shunt for said primary coil and being of relatively higher reluctance than the leg of said secondary coil and an armature bridging all of said legs, said armature being adjustable to increase and decrease the reluctance of the magnetic circuit passing through the leg of said secondary coil to respectively decrease and increase the induced voltage of said secondary coil.

4. In a variable voltage transformer, in combination, a primary coil, a secondary coil, an E-shaped core therefor, said coils being separately mounted on the end legs of said core, the middle leg of said core providing a magnetic shunt for said primary coil and being of relatively higher reluctance than the leg of said secondary coil and an armature common to the three legs of said core, said armature being longitudinally adjustable to increase and de-

crease the reluctance of the magnetic circuit passing through the leg of said secondary coil to respectively decrease and increase the induced voltage of said secondary coil.

5. In a variable voltage transformer, in combination, a primary coil, a secondary coil, a substantially E-shaped core therefor, said coils being mounted on two legs of said core and the third leg being of restricted cross sectional area and length relative to said former legs and a longitudinally adjustable armature common to said legs.

15 6. In a variable voltage transformer, the combination with a two-part inclosing casing, of an E-shaped core carried within one part of said casing, coils carried by said core, an adjustable armature associated 20 with said core, said armature being slidably supported on opposite sides between the parts of said casing and means operable from the outside of said casing for adjusting said armature.

25 7. In a variable voltage transformer, the combination with a two-part inclosing casing, of a laminated core mounted within said casing, coils carried by said core, an adjustable armature associated with said 30 core, said armature being slidably supported on opposite sides between the two parts of said casing, and means operable from the outside of said casing for adjusting said armature.

35 8. In a variable voltage transformer, the combination with an inclosing casing comprising two relatively inverted box-like sections, of a core mounted within said casing and secured to one of the sections thereof, 40 coils carried by said core, an armature cooperating with portions of said core and movable relatively thereto, said armature being slidably supported between projecting portions on both members of said casing and a screw operable from the outside 45 of said casing for adjusting said armature.

9. In a variable voltage transformer, the combination with an inclosing casing comprising two relatively inverted box-like sec-

tions, of an E-shaped core carried within 50 said casing and secured to one of the sections thereof, a coil mounted on each of the end legs of said core, an armature cooperating with the end legs of said core and adjustable relatively thereto, said armature being slidably mounted between 55 projecting portions on each of the sections of said casing and a screw operable from the outside of said casing for adjusting said armature.

10. In a variable voltage transformer, the combination with an inclosing casing comprising two relatively inverted box-like sections, of a laminated E-shaped core mounted within said casing and secured to one of 60 the sections thereof, a coil carried on each of the end legs of said core, a laminated armature bridging the extremities of the end legs of said core, said armature being 65 slidably supported between projecting portions on each of the sections of said casing and a screw operable from the outside of 70 said casing for longitudinally adjusting said armature.

11. In a variable voltage transformer, the combination with an inclosing casing comprising two rectangular relatively inverted box-like sections provided with a plurality of ventilating openings, a flat E-shaped laminated core mounted within said casing 80 and secured to one of the sections thereof, a coil carried on each of the end legs of said core, a laminated armature bridging the extremities of the end legs of said core, said member being slidably supported 85 between projecting portions on each of the sections of said casing, a rotatable screw having an operating knob on the outside of said casing for longitudinally adjusting 90 said armature and resilient means secured to said armature and interposed between the same and the inside wall of said casing for yieldingly holding said armature in engagement with said core.

In witness whereof, I have hereunto subscribed my name.

ARTHUR SIMON.
